US00D886494S

(12) **United States Design Patent** (10) **Patent No.:** **US D886,494 S**
Liu (45) **Date of Patent:** **** Jun. 9, 2020**

(54) **SET OF SEAT CUSHIONS**

(71) Applicant: **EVOLUTION TECHNOLOGIES INC.**, Port Coquitlam (CA)

(72) Inventor: **Julian Liu**, Port Moody (CA)

(73) Assignee: **EVOLUTION TECHNOLOGIES INC.**, Port Coquitlam (CA)

(**) Term: **15 Years**

(21) Appl. No.: **29/574,621**

(22) Filed: **Aug. 17, 2016**

(30) **Foreign Application Priority Data**

Feb. 26, 2016 (CA) 167113

(51) LOC (12) Cl. **06-09**

(52) U.S. Cl.

USPC **D6/601**

(58) **Field of Classification Search**

USPC D6/333, 349, 355, 375, 388, 512, 563, D6/564, 595, 596, 601, 604, 611, 707, D6/715, 716, 716.1; D24/183-185, 234; D21/803, 804, 805, 809; 5/401, 420, 5/600, 630, 631, 632, 633, 635, 636, 638, 5/639, 646, 652, 652.1, 655, 703, 730; 297/1, 2, 4, 93, 180.11, 195.1, 195.11, 297/195.13, 393, 397, 452.12, 452.14, 297/452.15, 452.21, 452.24, 452.26, 297/452.48, 452.62, 482

(57) **CLAIM**

The ornamental design for a set of seat cushions, as shown and described.

DESCRIPTION

FIG. 1 is a perspective view of the set of seat cushions, showing the front and top sides thereof; FIG. 2 is a top view thereof;

FIG. 3 is a bottom view thereof;

FIG. 4 is a left side thereof;

FIG. 5 is a right side thereof;

FIG. 6 is a front view thereof; and,

FIG. 7 is a rear view thereof.

The broken lines in the drawings are included for the purpose of illustrating subject matter that forms no part of the claimed design.

The stitching shown in dotted lines is part of the claimed design.

1 Claim, 7 Drawing Sheets
